Fig. 5.

FIG. 1 is a top perspective view of a foldable canopy for bicycles embodying my new design, with the canopy disposed in horizontal position;

FIG. 2 is a side elevational view of the same, with a portion of a conventional bicycle shown in phantom lines merely for the purpose of showing the orientation of the canopy with respect to the bicycle;

FIG. 3 is a rear elevational view of the same;

FIG. 4 is a side elevational view taken from the side opposite FIG. 2 showing the canopy in vertical position, with a portion of a conventional bicycle shown in phantom lines merely for the purpose of showing the orientation of the canopy with respect to the bicycle;

FIG. 5 is a rear elevational view of the same with the canopy in vertical position.

I claim:

The ornamental design for a foldable canopy for bicycles, substantially as shown and described.
